REGULATOR FOR HOT WATER HEATERS

Filed May 11, 1927

INVENTOR:
John H. Grininger
BY David E. Larsen
ATTORNEY.

UNITED STATES PATENT OFFICE

JOHN H. GRININGER, OF ST. PAUL, MINNESOTA

REGULATOR FOR HOT-WATER HEATERS

Application filed May 11, 1927. Serial No. 190,514.

My invention relates to a device for regulating hot water heaters of the well known usual type for heating hot water tanks for domestic use. The main object of the invention is to provide a simple and efficient device for turning on and off the gas or liquid fuel in a hot water heater by means accessible from or near a kitchen sink or other convenient place in a building but remote 10 from such heater.

In the accompanying drawing:

Fig. 1 is an elevation of a floor in section, portions of a kitchen and basement and embodying my complete device showing two 15 forms of primary operating devices one of which is in operative connection with a so-called gas water-heater.

Fig. 2 is an enlarged detail end view of the rock shaft with rod 18 in vertical relation thereto, about as at line 2-2 in Fig. 1.

Fig. 3 is an enlarged detail elevation of the fuel burner operating means involved in my device.

Fig. 4 is a partly longitudinal sectional elevation of a preferred type of water valve used in the operation of my device.

Referring to the drawing by reference numerals, 5 designates the jacket of the usual 30 type of upright gas water heater in which is mounted the usual water coil 6 heated by either a gas or oil burner 7 connected by a pipe 8 to a source of fuel, said pipe 8 having a valve 9 and a pilot light pipe 10 for igniting the fuel at burner 7. All said parts are usually installed in a basement in proximity to a water tank (not shown), and connected with said coil 6. 11 is a floor on joists 12, and 13 is a portion of a wall above floor 35 11 supported by a suitable post as to the right in Fig. 1.

My device in its preferred form comprises a hand lever 16' for oscillating its vertical shaft 16S' as in the upper central part of 45 Fig. 1, the said shaft 16S' being of a length determined by the location of lever 16' above the basement or other room in which the water heater is located, the lower end of it is supported in a bearing 35 and near said 50 end has a lever 17' pivotally connected to a

horizontally disposed reach rod 18', the opposite end of said rod 18' being connected to a lever 19' fulcrumed on a rock shaft 20' journaled in suitable hanger brackets 21' fixed to the floor joists 12 as in main part of Fig. 1. Said rock shaft carries a lever 22 which has its free end pivotally connected to the upper end of a secondary reach rod 23 extending downwardly and connected to a lever 24 operating a fuel control valve 9. It is obvious that the hand lever may be one, two or more floors above the floor 11 under which the water heating apparatus is located.

At the left in upper part of Fig. 1 the lever 16 is oscillatable in a vertical plane and its shaft 16S is journaled horizontally in an indicator disc 15 fixed on wall 13 by screws 15B, operative connection being established between lever 17 and 19 by the rod 18 being in upright position. Disc 15 may be used with either the horizontal or vertically operated lever 16. 15B are screws for fixing the said disc, as described. The lower half of said disc comprises, as shown, an outward shield 15S with a center bearing 15S' for the shank or shaft 16S as the case may be.

25 15 is a circular plate on shank 16S of lever 16 and with one half colored red, said red area being fully exposed outwardly of shield 15S when gas is turned on full. When crank 16 is turned as from full to dotted line position (to the left in Fig. 1) only half of said red area is exposed and occupants of a building will know that the gas is turned off and vice-versa when the entire red area is exposed.

20 It is obvious that a safety valve must be provided to prevent over-heating of a tank. For this purpose, I provide another lever 26 near end of rock shaft 20, said lever engaging the bail 27B of a suspended cylindrical bucket 27. Said lever projects in opposite direction from shaft 20 relative to lever 22 and thus when the latter is swung down to open the gas passage, the lever 26 is swung upwardly raising bucket 27 (see Figs. 1 and 2). This movement causes the opening of a

100

water valve which allows water to drip into bucket 27 gradually filling the latter until its weight pulls lever 26 down and oscillates shaft 20 so that rod 23 is raised and fuel is shut off. Certain water supply means comprise a feed pipe 28 connected to a source of water and has an outlet 28A to a needle valve seat 28S for a needle valve 20V comprising an integral part of shaft 20, threaded into a sleeve 29 which is also threaded for pipe 28. Oscillation of rock shaft 20 as described causes the threaded needle valve 20V to "creep" within sleeve 29 and move away from seat 28S allowing water to circulate through an aperture 29A in sleeve 29 thence through a suitable outlet 30 located so as to drop water into bucket 27 (see Fig. 1). The rate of flow of water may be varied as desired to fill bucket 27 which has an apertured bottom 27C and a piston-like false bottom 31 with a downwardly projecting pin 31P normally protruding through said bottom 27C. The member 31 is also apertured, but not to correspond with the apertures in bottom 27C so that water in the bucket will normally press parts 31 and 27C together in water tight condition. It will be readily understood that the lower end of bucket 27 is normally within a funnel 32 having an outlet pipe 33 and a web 32W near its outlet. When the bucket 27 becomes sufficiently heavy from the water in it, it drops down, pin 31P strikes web 33, piston 31 is stopped and bottom 27C of the bucket is separated from it and water escapes from bucket 27 to outlet 33. This dropping movement of the bucket oscillates the shaft 20 and other parts connected with the fuel valve, whereby the latter shuts off the fuel to the burner.

In Fig. 3 a preferred type of lever 24 is shown and comprises a piece of bar metal hingedly connected at 24A to a curved lower end 23L of rod 23, said bar 24 being bifurcated as at 24B to straddle and frictionally engage the flat valve stem part 9F, said bifurcated part extending away from said lever and closed together and threaded for a nut 34. Adjustment of said nut causes the lever 24 to clamp the valve piece 9F securely.

The use of my device has been fully disclosed in the preceding description of my device. Various other modifications may be involved during installation of my device but these may be construed as being embodied in the scope and spirit of the invention.

I claim:

1. A regulator for hot water heaters having a water coil heated by a burner having a fuel feed pipe and a valve therein, said regulating device comprising a primary rock shaft and a hand lever thereon in remote location from said burner; a lever on said shaft, a secondary horizontally mounted rock shaft, a lever on said primary shaft and

another lever on the adjacent part of the secondary rock shaft, a reach rod connecting said levers and adapted to impart oscillating movement to said secondary rock shaft, a lever fulcrumed on said latter shaft intermediate its ends, an upright reach rod extending from said latter lever and its lower end operatively connected to said fuel valve, and a trip lever on the further end of said secondary rock shaft arranged to be swung upwardly when the secondary rock shaft is tilted to open the fuel valve, and a tripping device operatively connected to said latter lever to automatically shut off the fuel. 70 75 80

2. A regulator for hot water heaters having a water coil heated by a burner having a fuel feed pipe and a valve therein, said regulating device comprising a primary rock shaft and a hand lever thereon in remote location from said burner; a lever on said shaft, a secondary horizontally mounted rock shaft, a lever on said primary shaft and another lever on the adjacent part of the secondary rock shaft, a reach rod connecting said levers and adapted to impart oscillating movement to said secondary rock shaft, a lever fulcrumed on said latter shaft intermediate its ends, an upright reach rod extending from said latter lever and its lower end operatively connected to said fuel valve, and a trip lever on the further end of said secondary rock shaft arranged to be swung upwardly when the secondary rock shaft is tilted to open the fuel valve, and a tripping device operatively connected to said latter lever to automatically shut off the fuel, and a visible signal device arranged in a plane parallel to the movement of said hand lever and comprising a fixed shield with a semi-circular opening concentric of said primary shaft, a disc fixed on said latter shaft within said shield and having a colored area arranged to be exposed in the opening of said shield according to the position of the fuel valve and the position of said hand lever. 90 95 100 105 110

In testimony whereof I affix my signature.

JOHN H. GRININGER.
